UNITED STATES PATENT OFFICE.

CHARLES H. PALMER, OF NEW YORK, N. Y.

SEWING-MACHINE.

SPECIFICATION forming part of Letters Patent No. 268,122, dated November 28, 1882.

Application filed January 11, 1882. (No model.)

To all whom it may concern:

Be it known that I, CHARLES H. PALMER, a citizen of the United States, residing in the city, county, and State of New York, have invented certain new and useful Improvements relating to Sewing-Machines, of which the following is a specification.

My experiments have been made with machines for sewing straw braid. The improved machine may be used for various analogous classes of work where there is but little breadth of the material extending into the machine beyond the line of the seam. I will describe it as sewing straw braid.

The invention relates to the feeder and associated devices. The feeder may be of the ordinary form, except for a ledge or bearing-surface farther back in the machine. The presser-foot is provided with an arm reaching correspondingly back. When there is braid in the machine and the feeder acts thereon, compressing the same between itself and the presser-foot, the action proceeds in all respects in the ordinary manner; but when through any contingency the machine works empty the teeth of the feeding device are not allowed to come in contact with the presser-foot. The back surface referred to on the feeder at each lift of the feeder comes in contact with the back arm on the presser-foot and lifts it.

The following is a description of what I consider the best means of carrying out the invention.

The accompanying drawings form a part of this specification.

Figure 1 is a side elevation, partly in section, showing all the novel parts, with so much of the ordinary parts as is necessary to indicate their relation thereto. Fig. 2 is a front view of the same. Fig. 3 represents a detail, being a plan view of the presser-foot.

Similar letters of reference indicate corresponding parts in all the figures. The parts not shown may be of any ordinary or suitable construction.

A is the framing; A', the work-plate; B, the main shaft. B³ is a crank thereon engaging the feeder.

G is the presser-bar, urged downward by a spring, (not shown,) in any ordinary or suitable manner.

G' is the presser-foot.

G² is an arm or backward extension from the presser-foot, which performs an important function.

H is the feeder. It is what is known as the "four-motion feed," actuated by the eccentric or crank B³ on the shaft B, before referred to. The feed is gaged in any ordinary or suitable manner. The toothed portion, which rises through a suitable orifice in the work-plate A', and is effective in acting on the work, is marked H'. An arm or extension reaching upward at a point farther in the rear (marked H²) is smooth. Its height is carefully adjusted, so that it will come in contact with the part G² of the presser-foot and hold it just clear of the teeth H' when the machine is working idly, without any fabric under the presser-foot, but will not touch the part G² and will be of no effect when there is braid in the machine, because the teeth H' will lift the presser-foot through the medium of the braid. The back extension, H², of the feeder may be made in one with the front portion, H', and with the main body H, and some of the benefits of the invention will be thereby obtained; but I make it in a separate piece, secured adjustably to the part H by the screw P, standing in a vertical slot in the part H', as shown. I thus provide for adjusting the height of the two parts, H' H², relatively to each other. This may become desirable to allow for the difference of wear of the teeth H' and the back extension, H².

My improved machine involves little spring and little liability of derangement. The parts may be very light. The inertia is little and the vibration slight.

Most of the ordinary attachments and appliances used in sewing-machines may be used with this invention.

This application is a division of an application for Letters Patent for sewing-machines filed in United States Patent Office by me August 12, 1880, Serial No. 15,250.

I claim as my invention—

1. In a sewing-machine, the device H², rising and sinking with the feed, in combination therewith, and arranged to strike the presser-foot or a part connected thereto, so as to raise it out of contact with the feed at each rise of the lat-

ter, substantially as and for the purposes herein specified.

2. In a sewing-machine, the presser-bar G, presser-foot G', and back extension, G², in combination with the feeder H, toothed portion H', and back extension, H², formed in a separate piece and adjusted relatively to the part H' by the screw P, as herein specified.

In testimony whereof I have hereunto set my hand, at New York city aforesaid, this 10th day 10 of January, 1882, in the presence of two subscribing witnesses.

CHARLES H. PALMER.
